FLAT TERMINAL FITTING

William A. Meighan, Portland, Oreg.

Application November 3, 1944, Serial No. 561,788

6 Claims. (Cl. 24—129)

1

The object of my invention is to provide a flat terminal fitting which is so constructed that the end of a wire rope or cable can be secured thereto without having to be passed end-first through a close fitting eye or orifice. Wire rope tends to be frayed out at an end where it is cut. That is, wire rope is made of elastic wire in strands formed into a cable and when the rope is cut said free ends tend to spread out or to "bloom" so as to present a substantially larger cross-sectional area than that of the cable. It is common to whip or bind said wire ends together but it is impractical to bind them so tightly that they do not fray or "bloom." Thus, if the end of the cable thus frayed has to be pushed endwise through an eye it presents substantial difficulty. I have discovered that a terminal fitting can be constructed in which the convolutions of a knot may be formed and held without necessitating said end to be forced longitudinally through such a close fitting eye and yet a tight knot can be formed which will not slip and will not tend to become untied even though the rope is quite stiff and elastic.

The present invention relates to the same general subject matter as do previous patents issued to me, namely: patent entitled Wire rope fitting, issued September 26, 1939, No. 2, 174,192; patent entitled Rope fitting, issued March 12, 1940, No. 2,193,236.

Further details of my invention and the operation thereof are hereinafter described with reference to the accompanying drawings, in which:

Fig. 1 is an elevation of a flat terminal fitting embodying my invention;

Fig. 2 is a more or less diagrammatic illustration, shown in perspective and on a reduced scale, of the manner in which the frayed end of a wire rope may easily be passed sidewise through an elongated eye, initially to engage said wire rope fitting;

Fig. 3 is a similar view, but on a slightly larger scale, illustrating how a rope may be formed into a loosely formed knot about said fitting; and

Fig. 4 is an elevation of said fitting showing the manner in which the tightened knot engages various parts of said fitting to prevent slipping or inadvertent disengagement.

A wire rope fitting 1 is made as an integral structure by forging, casting, stamping, or other appropriate manufacturing procedure and is substantially bifurcated in elevation. The ends of said bifurcation terminate in two opposed spaced free ends, or eyes 2, having holes 3 formed therein to receive a pin or other keeper. Said fitting

2

encompasses a more or less keyhole-shaped recess 4. Above the portion of said recess of greater breadth is a bail-like member 5 defining an elongated aperture 6 therein.

Extending laterally from said fitting at one side of said recess 4 is an up-standing member 7 resembling a thumb, and projecting downwardly below the general plane of said aperture is a pair of spaced finger-like members 8 and 9, respectively. The member 8 curves downwardly and overlies the upper portion of said keyhole-shaped recess 4 while the finger-like member 9 overlies the portion of the bifurcated fitting spaced from said member 7. Said two finger-like members and the thumb-like member between them define a transversely disposed way 10 and said members 7, 8 and 9 are spaced laterally apart at substantially uniform distances. It is to be noted in Figs. 2 and 4 that said two members 8 and 9 extend downwardly below the tip of the member 7 so that the finger members 8 and 9 from above, and the thumb-like member 7 from below, wholly encompass the way 10. Lying between said member 7 and member 8 is a more or less longitudinally disposed slot 11 and between the fingers 8 and 9 is another slot 12. Preferably, the width of the slot 11 closely approximates the diameter of the cable 13 as to be accommodated therein. That is, the free, and usually frayed, cable end 13a, may be slipped sidewise through the elongated aperture 6, as is indicated in Fig. 2, and then a substantial portion of the end of said cable is passed therethrough and the cable end 13a may be slid laterally into slot 11 between the members 7 and 8, when said cable is arranged substantially at 1 o'clock considering the position of the hands on the face of a clock. The intermediate portions of said cable may then be moved under the finger-like members 8 and 9 and a loop may be formed, passing through the recess 4 as the cable is illustrated in Fig. 3. Then, when the terminal fitting is held and tension is applied to the cable, the rope may be tightened into a knot, as is illustrated in Fig. 4. It is to be noted that the end of the cable lying in the transversely disposed way 10 is curved slightly. That is, a slight kink is formed in it. This is important because it tends to lock said free end in said way before tension is applied and this prevents the cable from slipping out of the position in which it is initially arranged. Continued and increased tension tends to bind the cable about the portions of the wire rope fitting, overlying other portions thereof, to prevent slipping. The close fit between the members 7 and 8, that is, the

limited width of the slot 11, tends to prevent the end of the cable from looping about and passing inadvertently through said slot when tension is applied. Wire rope or cable being twisted and wound strand upon strand tends to untwist and, unless it is firmly held, it may sometimes fly free. It is essential that wire rope fittings of this character be quickly and securely tied, not only for the end use of securing the end of a cable, but also to eliminate injury to workmen. It takes substantial pull on a cable to form a knot from its form as shown in Fig. 3 to its form as shown in Fig. 4, and if a cable is permitted to fly free it would sweep out and possibly injure someone standing near. Said inadvertent detachment is prevented because said cable cannot easily pass laterally through the slot 11. That is, when it lies in the way 10 it is kinked slightly. The elasticity of the wire rope tends to resist said kinking and thus binds said ends beneath said two finger-like members 8 and 9, and above and within the up-standing thumb-like member 7. Said fitting resembles quite closely the thumb, forefinger and middle fingers of the right hand when partially clenched.

This type of wire rope has particular utility when used in connection with relatively light-weight cable and may be easily and quickly tied to the end of a wire rope wherever there is a place to secure the fitting and to apply tension thereto. Even when used with relatively large sizes of wire rope it can be tied to a terminal fitting by a single workman with his bare hands.

I claim:

1. An integral, flat terminal rope fitting having an elongated body, comprising a bifurcated member having securing elements on the free ends thereof, the central portion thereof defining a recess, an apertured member secured to said bifurcated member and projecting longitudinally therefrom, and a series of spaced, opposed claw-like fingers extending laterally from the face of said bifurcated member and defining an inclosed transverse rope way.

2. An integral, flat terminal rope fitting having an elongated body, comprising a bifurcated member having securing elements on the free ends thereof, the central portion thereof defining a recess, an apertured member secured to said bifurcated member and projecting longitudinally therefrom and a series of spaced, opposed claw-like fingers extending laterally from the face of said bifurcated member and defining an inclosed transverse rope way, the space between two opposed fingers closely approximating the diameter of the rope to be secured to said fitting.

3. An integral, flat terminal rope fitting having an elongated body, comprising a bifurcated member having securing elements on the free ends thereof, the central portion thereof defining a

5 recess, an apertured member secured to said bifurcated member and projecting longitudinally therefrom, and a series of spaced, opposed claw-like fingers extending laterally from the face of said bifurcated member and defining an inclosed transverse rope way, said fingers defining a bow in said way lying in the general plane of said fitting.

4. An integral, flat terminal rope fitting having an elongated body, comprising a bifurcated member having securing elements on the free ends thereof, the central portion thereof defining a recess, an apertured member secured to said bifurcated member and projecting longitudinally therefrom, and a series of spaced, opposed claw-like fingers extending laterally from the face of said bifurcated member and defining an inclosed transverse rope way, said fingers defining a bow in said way lying in the general plane of said fitting and in a direction away from said apertured member.

5. An integral, flat terminal rope fitting having an elongated body, comprising a bifurcated member having securing elements on the free ends thereof, the central portion thereof defining a keyhole recess, an apertured member secured to said bifurcated member and projecting longitudinally therefrom, and a series of spaced, opposed claw-like fingers extending laterally from the face of said bifurcated member and defining an inclosed transverse rope way.

6. An integral, flat terminal rope fitting having an elongated body, comprising a bifurcated member having securing elements on the free ends thereof, the central portion thereof defining a keyhole recess, an apertured member secured to said bifurcated member and projecting longitudinally therefrom, and a series of spaced, opposed claw-like fingers extending laterally from the face of said bifurcated member and defining an inclosed transverse rope way, the space between two opposed fingers closely approximating the diameter of the rope to be secured to said fitting, and said fingers being proportioned and arranged to define a bow in said way lying in the general plane of said fitting and in a direction away from said apertured member.
